UNITED STATES PATENT OFFICE

2,552,691

PORTABLE STRUCTURE HAVING PIVOTED
BOXLIKE PORTIONSWilliam Arthur Cecil Saunders-Knox-Gore,
Countess Wear, near Exeter, EnglandApplication April 20, 1946, Serial No. 663,658
In Great Britain November 23, 1944Section 1, Public Law 690, August 8, 1946
Patent expires November 23, 1964

1 Claim. (Cl. 296—23)

1 This invention comprises improvements in portable structures adapted for use as dwellings and has for its object to provide a structure which is capable of being readily enlarged to afford living and sleeping accommodation so that, for example, a compact structure capable of being carried on or trailed behind a motor or horse vehicle, or carried on a barge or motor craft can readily be enlarged to provide a bungalow or houseboat when a suitable site or anchorage is reached.

According to this invention, a portable dwelling structure comprises an inner and an outer component which can be turned in relation to one another so as to intersect and thereby provide additional accommodation due to the increased area occupied by the components when intersecting. For example, the two components may be nearly similar in size and shape and each may be an oblong box-like body with slightly rounded ends, the inner one being dimensioned to fit nicely within the outer one and mounted on a swivel so as to be capable of being turned easily into a position at right angles to the outer component.

One embodiment of the invention as applied, by way of example, to a trailer will now be described with reference to the accompanying drawings in which:

Figure 1 is a side elevation of the structure in the closed travelling condition,

Figure 2 an end view, and

Figure 3 a plan view thereof.

Figure 4 is a plan view of the structure in the opened condition, and

Figure 5 a perspective view of the same as seen in the direction of the arrow V in Figure 4.

In this example, the portable dwelling structure consists of two compartments 1, 2 of nearly similar size and shape each of which comprises an oblong box-like body with part-circular end walls 3, 4. The inner body 1 is dimensioned to fit snugly within the outer body 2 (Figure 3) and is mounted therein by means of upper and lower pivots 5, 6 so as to be capable of being turned easily into a position at right angles to the outer body (Figure 4). The end walls 3, 4 are shaped to conform with arcs struck from this pivotal axis. The sides of the inner body are fitted with permanent walls 7 and any permanent internal partitions, for example 8, which in the outer body 2 might impede movement of the inner body 1, are preferably also provided in the latter. The sides of the outer body 2 are fitted with permanent short walls 9 on opposite

sides at opposite ends, but are open at 10 to permit the inner body 1 to be swung in. Thus, when the latter has been turned into the open position at right angles to the outer body, only the comparatively short externally projecting parts of the openings 10 in the side walls require to be covered or filled in. This may be done by means of curtains 11 (Figure 5), by flaps hingedly attached to the outer body 2 or inner body 1, by devices such as roller blinds, or the like. Each of the components 1, 2 may be provided with appropriate windows 12 and doors 13 and with other accessories such as ventilators.

By way of illustration, let it be assumed that the floor area of the outer body 2 is 21' x 7'. In this case, the floor area of the inner body 1 will be only slightly less as will also the floor area available for use when the inner body is turned into alignment with and wholly contained within the outer body (Figure 3). However, upon turning the inner body until it is at right angles to the outer body, so that the complete structure forms a cross (Figure 4), not only is the aforesaid floor area available, but floor areas of 7' x 7' at each end of the outer body 2 become available in addition.

Locking means (not shown) may be provided for retaining the inner body 1 in the travelling position and/or in the opened position in relation to the outer body 2. Strut devices, such as jacks 14, may be provided for supporting or steadyng overhanging parts. The outer body may be mounted either fixedly or detachably on a trailer chassis 15, as shown, or on a barge or other carrier and, during transport, the inner body will naturally be in the completely housed longitudinal position. During such transport or until the structure is required in an expanded condition, compartments 16, 17, 18 (Figure 3) of the inner body are available for instance, for use as scullery (or bath room and lavatory), kitchen and lounge. When the structure has been expanded, the end spaces or compartments 19 (Figure 4) of the outer body 2, vacated by the turning of the inner body 1, become available, as required, as reception rooms or bed rooms or as additional bed rooms if compartments 17 and 18 are already fitted with bunks or beds.

In one convenient arrangement, folding beds are carried complete with their bedding in cupboard-like recesses 20 formed in the side walls of the inner body. Any required number of such beds 21 can be lowered into the additional spaces 19 when the components 1, 2 are at right angles. The doors closing these bed-cupboards may also

be lowered to form tables when the beds are not in use.

The doors and windows will be arranged to suit requirements in both conditions of the structure. For instance, in the travelling condition, the side door 13¹ (Figure 3) will afford access from outside, and, in the expanded condition, the front door 13² (Figure 4).

If desired, the outer component 2 may also be mounted on a swivel on its chassis 15, barge or carrier, so that the whole structure can be turned in any direction to suit prevailing weather conditions.

A rack and pinion gear or other suitable means may be provided for rotating the inner component 1 in relation to the outer component 2 and also, if desired, for rotating the outer component on its swivel mounting on a carrier. Roller or other anti-friction bearings may be provided.

Folding jacks provided at suitable points under the floor of the outer component may be arranged to enable the whole structure to be lifted slightly so that a trailer chassis can be withdrawn and the structure lowered onto the ground or onto a suitable semi-permanent foundation built thereon or to any desired height on the jacks themselves. In this way only one wheeled chassis may be required for the removal in turn of a number of structures where, for example, it might be desired to remove a whole holiday camp or a colony of workmen's dwellings.

When the structure is used on a barge or motor craft, inflatable pontoons may be provided for attachment to the outer ends of the inner component 1 to help steady the structure.

It will be apparent that although the outer component 2 may generally be regarded as the fixedly mounted component and the inner component 1 as the movable component capable of being turned in relation to the outer component it is possible to modify the design so that the inner component is the relatively fixed component and the outer component is the movable one.

The structure is not necessarily limited to two components but may comprise a greater number of components. For example, three components may be used and may be adjustable in relation to one another so as to produce a six-pointed star-shaped structure instead of the cross-shaped

structure produced by two components. Alternatively filling pieces for roof, wall and floor gaps between two or more components may be arranged to complete a circular or polygonal structure.

A composite structure embodying these improvements is capable of being produced from very light material and nevertheless of possessing considerable strength when it is remembered that the two components, which normally fit closely one within the other, are of box formation and therefore have girder-like qualities.

The term "dwelling" includes a number of uses to which the improved structures may be put, as for example ordinary living quarters, holiday camps, temporary hospitals and sanatoria, and so on.

I claim:

20 Portable dwelling structure comprising an inner and an outer component nearly similar in size and shape and disposed one in the other, each being an oblong box-like body with arcuate ends, and centrally disposed vertical pivot means connecting the said components, one of said components being mounted upon the said pivot means so as to be capable of being turned easily about the vertical axis of said pivot between a position in which it is housed snugly within the outer component and a position at right angles thereto.
